UNITED STATES PATENT OFFICE.

HORATIO SMITH, OF KIDDERMINSTER, ENGLAND, ASSIGNOR TO WILLIAM MANSELL DAINTREY, OF NEW YORK.

DESIGN FOR A CARPET.

SPECIFICATION forming part of Design No. 12,946, dated May 23, 1882.

Application filed March 14, 1882. Term of patent 3½ years. Registered in England February 22, 1881, No. 362,009.

To all whom it may concern:

Be it known that I, HORATIO SMITH, of Kidderminster, England, have invented a new and original Design for Carpets, of which the following is a specification.

This invention relates to a new and original design for carpets and similar fabrics; and it consists in the novel grouping and configuration of parts hereinafter more fully described.

10 The accompanying photograph illustrates a face view of a carpet having my new design.

The letter D represents a branch bearing on it pointed oblong leaves and circular flowers.

15 The letter G represents a branch bearing oval rounded leaves and large circular flowers.

E is a vine-like figure bearing oval leaves, rose-like flowers, and circular buds.

20 F is a figure resembling a branch with oval leaves, circular buds, and rose-like open flowers growing thereon.

The figure h is a branch with oval leaves.

g is a background composed of small-patterned squares resembling basket woven-work.

25 h is a background resembling a series of interlacing strips.

The background i consists of a series of rectangular figures, as shown.

The background l is a series of diamond-shaped figures connected by straight lines.

30 The background m consists of triangles and small circles arranged to form a pattern.

The background n is composed of circular figures and crosses arranged in a regular pattern.

35 The background o consists of oblique ornamented bands running parallel to each other.

The background r consists of broken lines crossing each other at right angles.

I claim—

1. The design for carpets, consisting of the 40 figure D, substantially as shown.

2. The design for carpets, consisting of the figure E, substantially as shown.

3. The design for carpets, consisting of the figure G, substantially as shown.

4. The design for carpets, consisting of the figure F, substantially as shown. 45

5. The design for carpets, consisting of the figure g, substantially as shown.

6. The design for carpets, consisting of the figure h, substantially as shown. 50

7. The design for carpets, consisting of the figure i, substantially as shown.

8. The design for carpets, consisting of the figure l, substantially as shown. 55

9. The design for carpets, consisting of the figure n, substantially as shown.

10. The design for carpets, consisting of the figure m, substantially as shown.

11. The design for carpets, consisting of the figure o, substantially as shown. 60

12. The design for carpets, consisting of the figure r, substantially as shown.

13. The design for carpets, consisting of the figures D E F G g h i o l n m r, substantially 65 as shown.

The foregoing specification of my invention signed by me this 2d day of February, 1882.

HORATIO SMITH.
